CLAIM

The ornamental design for an electrical discharge machine, as shown and described.

DESCRIPTION

FIG. 1 is a perspective view of the front, right, and top side of a electrical discharge machine showing an embodiment of our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference front view in a state where a work tank door is put down; and,

FIG. 9 is a reference front view in a state where a safety door is raised up.

The broken lines shown represent unclaimed subject matter of an electrical discharge machine and form no part of the claimed design.
